ROTARY PISTON MACHINE

Paul Sobek, Vienna, Germany, assignor to Eric Benjamin, New York, N. Y.

Application July 6, 1938, Serial No. 217,832
In Austria July 13, 1937

3 Claims. (Cl. 103—129)

The present invention relates to a rotary piston engine, which may be used as a rotary pump, compressor, hydraulic drive gear, power engine, internal combustion motor or the like.

The main disadvantage of the known uni-axial rotary piston machines is the necessity of providing one or more valves, and of bi-axial or tri-axial rotary piston machines, is the use of elements with complicated conformations which pass by each other.

A further decided disadvantage of prior rotary engines is the fact that they cannot be regulated.

Also prior rotary piston engines, with which attempts have been made to develop relative speed between the pistons, have a rigidity of construction which makes it impossible to regulate their capacity.

One object of the present invention is to provide a new and improved rotary piston engine, in which the above mentioned disadvantages have been overcome.

Another object is to provide a rotary piston machine whose capacity (volume or pressure) can be varied any predetermined amount, either while the machine is at rest, or while it is operating, without the use of a special governor. This construction allows the use of a variable speed drive at all stages from complete idleness to highest speed.

In the embodiment of my invention, the relative angular velocity between the two rotary elements is a function of the angle alpha, formed by these rotary elements at a rest predetermined position of the cross-head link interconnecting said elements. With an increase of this angle alpha, the relative angular velocity of the two rotary elements decreases, and at an angle of 180°, the two rotary elements have the same angular velocity. Thus, an idling position is attained, in which the machine used either as a suction engine, or as a power engine has no output.

The desired adjustment of the angle alpha between the two rotary elements, can for instance, be achieved by increasing or by decreasing the distance a between the axis of rotation of the cross-head link and the axis of rotation of the rotary elements. Thus, when a equals zero, the angle alpha reaches the aforementioned value of 180°. Decreasing the angle alpha increases the capacity of the machine. Furthermore by changing the distance a and thus changing the angle alpha, a regulation can be effected while the rotary elements are in motion. This

can be done manually or automatically, as for instance by adjustable spring pressure. The machine may be so constructed, that with changes in the distance a , corresponding regulation or displacement at the intake and outlet ports occurs.

Each of the pistons may be in the shape of a sector of a circle. With this construction, the most favorable sealing effect is obtained, especially with motors and compressors, and particularly when the angle of the piston sector is at least equal to the angle alpha. I have found that very favorable results can be obtained with an angle of 90° for the piston sector.

15 In one embodiment of the invention, the two pistons have drive connections with a solid and a tubular shaft respectively.

It is known, that if a piston engine is used as a compressor, difficulties in starting, large power consumption, undesirable development of heat, and other disadvantages are caused by too great a pre-compression. According to the present invention, regulation of the pre-compression is provided for. Such regulation, can for example, be effected by increasing or decreasing the outlet ports by means of a slide valve, thus terminating the pre-compression at an earlier or later time. In another modification, a series of apertures may be arranged in front of the outlet, which may be controlled by means of a slide valve or the like, thereby causing an earlier or later termination of the pre-compression.

The rotary piston machine, according to the present invention, can also be constructed as a 20 multiple-stage device, by arranging two cylinders side by side and by providing a cross-head link, having a double drive between them, or by arranging the second cylinder in series or tandem with the first, thus obtaining a two-stage device. In either case. The side by side arrangement may also be combined with the series or tandem arrangement to produce a four or more stage device.

In the accompanying drawings, there is shown for purposes of illustration, various forms of devices, embodying the invention, in which:

Fig. 1 is a vertical section, somewhat diagrammatic, and taken through the center of one embodiment of the present invention on line 1—1 of Fig. 3.

50 Fig. 2 is an end view, partly in section, and somewhat diagrammatic of the device of Fig. 1, shown with the front casing wall removed.

Fig. 3 is the other end view, partly diagrammatic, of the device of Fig. 1, with the link adjusting mechanism removed,

Fig. 4 is a diagram showing the relative positions of the pistons, in various phases thereof, for a predetermined setting of the angle alpha,

Fig. 5 is a diagram, showing the relative positions of the pistons for various adjustments of the angle alpha,

Fig. 6 is a section, partly diagrammatic, of another form of device, used as a drive or hydraulic gear mechanism,

Fig. 7 is a section, partly diagrammatic, of another form of device used as a compressor,

Figs. 8a, 8b, 8c and 8d are diagrams, showing respectively the various phases of an embodiment of my invention, employed as a combustion engine, and

Figs. 9 and 10 are respectively sections, somewhat diagrammatic, of different embodiments of the invention, for regulating the pre-compression of a rotary piston machine.

In the form of invention shown in Figs. 1 to 5, 20 the rotary piston machine comprises a casing 1, having an inlet 2, and an outlet 3. In the interior of this casing are two rotary elements, in the form of pistons 4 and 5, rotating on a common axis. Piston 5 is secured to a solid shaft 6, while piston 4 has a drive connection with a tubular shaft 7 encircling said shaft 6, and rotatable with respect thereto. This piston 4 is shown carried on the frontal side of a disc 9, connected to the tubular shaft 7. By means of such 30 or similar arrangements, the pistons 4 and 5 can be moved to and fro independently of each other.

The outer end of the solid shaft 6 as well as the tubular shaft 7 carry cranks 11 and 10 respectively. Each of these cranks 10 and 11 has at its end a crank pin 12, which is inserted in a sliding block 13. Both of these blocks 13 slide in a cross-head link 14, which is pivotally supported by means of a pivot 15 in a bearing 16. Instead of the sliding blocks 13, rollers or the like may 40 be used.

The cranks 10 and 11 and with them the pistons 4 and 5, form an angle alpha therebetween, the value of which depends upon the distance a between the center of the pivot 15, and the center of the shafts 6 and 7. When the link 14 is rotated about the axis of the pivot 15, the slide blocks 13, as well as the crank pin 12, are carried with it. As the distance between the link axis and slide blocks 13 changes continuously, the cranks 10 and 11 will have continuously changing angular velocities which continuously vary relatively.

At the starting position A—A of the link 14, shown in Fig. 4, the cranks 10 and 11 on account of the position B—B' of the elements 13, form the smallest possible angle. If the link is turned in the direction of the arrow into position A2—A2, crank 10 develops an increase and crank 11 develops a decrease in its respective angular velocity, and crank 10 begins to advance. At the link position A2—A2, the cranks 10 and 11 therefore will be in the positions B2 and B3 respectively; at the link position A3—A3, the cranks 10 and 11 will be in positions B4 and B5 respectively; and at the link position A4—A4, the cranks 10 and 11 will be in positions B6 and B7 respectively. After a half revolution of the link, the angle alpha will again be at its minimum, but the position of the cranks 10 and 11 will be reversed, that is, the crank 10 which was located on the left side, will now be on the right side, and vice versa. Since the pistons rotate with the cranks as mentioned above, and form the same angle at the starting position A—A of

the link as the angle between said cranks, the pistons 4 and 5 will maintain an angular relationship equal to that of said cranks.

The application of these principles to the function of a pump shows that the advance of the piston 4 in relation to the piston 5, causes an expansion of the space between said pistons, and consequently leads to a suction effect. While the crank 11 (Fig. 4), during a half revolution of the link, moves from B' to B (angle alpha), piston 5 moves into the former position of piston 4, and while crank 10 simultaneously moves from B to B', piston 4 moves into the former position of piston 5, through an angle of (360—alpha). The increase of the angle alpha, which was originally formed by the pistons, to the angle (360—alpha), causes an expansion of the chamber (volumetric area included by angle alpha), and accordingly creates suction. On the other side of the pistons, however, a reduction of the angle (360—alpha) to the angle alpha, causes a reduction of the chamber and hence a pressure effect. This function results in a double acting piston pump, which may also be constructed as a two-stage or multiple-stage device in order to obtain multiple effects. If the direction of rotation is reversed, the function of the intake and outlet 2 and 3 will be changed correspondingly. This description pertains more particularly to a rotary piston pump.

The regulation of the machine may be effected in a very simple manner, by changing the distance a between the axis of the pivot 15 and the axis of the shafts 6 and 7. In this manner the capacity of the pump may be changed. If the distance a is decreased, the angle alpha will be increased, and the angle (360—alpha) decreased, and the increase and reduction of space between the pistons 4 and 5 are changed correspondingly. By reducing the volume of the working cylinder, a smaller amount is sucked in, and a smaller amount is delivered. By adjusting the position of bearing 16 with reference to shaft 6, the delivery of the pump may be regulated, whilst the pump is running. By reducing the distance a to a_2 (Fig. 5), the angle alpha is changed to alpha 2. If the distance a becomes zero, the axis of the pivot 15 and the axis of shafts 6 and 7 will coincide, and alpha as well as (360—alpha) will amount to 180°. Under these conditions, the pistons will rotate with constant angular velocity, so that there is no suction and no delivery, and the machine simply idles. Thus, by adjusting the bearing 16, the delivery may be regulated from zero to a maximum, even while the pump is in motion. This regulation may be performed manually or automatically in response to the output pressure, and through the use of spring pressure. If the pre-adjusted maximum pressure in the pump is exceeded, the angle alpha between the pistons is changed, and the link will change its position in accordance with a set spring pressure. In the case of large pumps an adjustable hydraulic back pressure may advantageously be used instead of spring pressure.

In Fig. 1, manually operated means are somewhat diagrammatically shown, for adjusting the position of the pivotal support of the link 14 with respect to the axis of the shafts 6 and 7. In the specific form shown, this means includes a screw member 17, threaded into a standard 18, and having its upper end supporting the bearing 16. Fixed to this screw member 17 is a collar 19, having a series of spaced holes on its periphery for

receiving a suitable turning tool 20. The rotation of this collar 19 causes a corresponding rotation of the screw member 17, and effects the required adjustment of the bearing 16.

Inasmuch as in an adjustable pump the position of the pivot is changeable, the shaft 6 which in that case extends through the cover 17a (Fig. 1, dotted lines), is used as a driving shaft. The link 14 in this case, provides for the connection between the piston 5 and shaft 6. Simultaneously with the change in the distance a , the position or area of the openings of the ports or both may be changed through a connection with the link bearing. The possibility of a simple regulation of the rotary piston machine by merely shifting the link bearing 16 during operation, permits the use of the machine as a variable hydraulic gear. This is accomplished by connecting two pumps in series, one of them being driven as a primary element (generator) and the other as a secondary element (hydraulic motor). It is preferable to combine both parts structurally into one unit. If reverse motion of the machine is desired, the pivot 15 must be moved through and beyond the axis of shafts 6 and 7. Then the distance between the two axes will govern the speed of the reverse motion. In such case, the intake and outlet aperture will necessarily change their respective functions.

In Fig. 6 the intake port 2a and outlet port 3a are substantially wide at the periphery of the casing, and the ends of the pistons 4a and 5a have segmental port sealing sections of substantial length corresponding somewhat to the width of said ports. Between the pressure and the suction side a proper sealing of the ports is thereby provided. In this construction also, the piston 5a lags in relation to the piston 4a. Owing to the simplicity of construction, high temperatures need not be feared, and usual cooling and ventilation methods may therefore be applied in the ordinary way. The construction of Fig. 6 is particularly adapted for use as a variable hydraulic gear.

A pronounced drawback of compressors is their relatively large size compared to their capacity. By means of the present invention, especially as embodied in the form shown in Fig. 7, this drawback is largely overcome. In this embodiment of the invention, the pistons 4b and 5b are each in the form of a sector of a circle, and rotate in a casing 1b, having an intake port 2b and a discharge port 3b. By reason of the fact that the relative angle of the pistons can be reduced to practically zero, maximum discharge is assured, and the above mentioned drawback is overcome. This construction affords exceptionally good sealing possibilities which are not applicable to the ordinary piston compressor. On account of this, and also owing to the favorable cooling possibilities, extraordinarily high pressures can be obtained. Multiple-stage construction is also possible. Furthermore, the pistons 4b and 5b may be equipped with internal cooling. Thus by the use of the rotary piston machine of the present invention as a compressor, effects may be obtained, which owing to the aforementioned drawbacks of the ordinary piston compressor, are unattainable with the latter.

The use of the rotary piston engine according to the present invention as a steam engine, has first of all the advantage that no intake regulation by means of slides, slots or valves is necessary. Such regulation can be effected in a most simple manner in combination with the regula-

tion of the link pivot and with the aid of a suitable governor.

Furthermore, the rotary piston engine according to the present invention may also be used for internal combustion engines with particularly favorable results. Figs. 8a, 8b, 8c and 8d show the sequence of the phases in the case of a gasoline motor. The different phases are shown, as the pistons 4c and 5c start to diverge, and as they end their approaching movement, a cycle corresponding to a half revolution of the link.

In the phase shown in Fig. 8a, the exhaust is terminated, with subsequent start of suction in the space C between the pistons 4c and 5c. In 15 the space D between the pistons 4c and 5c the explosion is terminated and exhaust begins.

In the phase shown in Fig. 8b, the exhaust is terminated and suction begins in the space D between the pistons 4c and 5c. The suction is terminated and the compression starts in space C.

In the phase shown in Fig. 8c, compression is terminated and explosion begins in space C. Suction is terminated and compression begins in space D.

In the phase shown in Fig. 8d, compression is terminated and explosion starts in space D. Explosion is terminated and exhaust begins in space C.

The inlet and exhaust ports may either control themselves or known systems may be applied. They may be controlled by the piston peripheries or through the use of known systems of valve control. The use of the rotary piston machine according to the present invention affords again the possibility of regulating the changes of compression in a most simple manner, such as could not be attained by the hitherto known methods, merely by shifting the link pivot. As the machine according to the present invention does not contain parts which pass by one another, the possibilities of packing are as favorable as in reciprocating piston engines.

The invention is especially applicable for airplane engines. The double-action of the engine, its favorable operative connection, and its simple, effective cooling, afford the possibility of producing for the same capacity much smaller and considerably lighter engines than was hitherto possible with reciprocating pistons.

Fig. 9 shows a construction for regulating too high a pre-compression. This construction comprises a slide 21 arranged at the outlet 3d in a recess 22 of the casing 1d, in which rotate the pistons 4d and 5d. This slide may be shifted in varying degrees in the direction of the arrow F. In this way the pre-compression may be terminated earlier or later, and the desired regulation may be obtained either manually or automatically.

In the construction shown in Fig. 10, the recess 22 forms a wall 23, having a series of holes 24, controlled by a slide 21a in said recess. This slide 21a can be shifted in both directions as indicated by the arrow F, to cover or uncover the holes 24. Thus with the aid of said holes 24, the pre-compression can be terminated earlier or later, depending on the number of said holes covered by the slide 21a.

Although in the form of the invention shown in Figs. 9 and 10, the slides 21 and 21a are disposed for control of the discharge ports 3d, it must be understood that a similar arrangement may be provided for the inlet ports 2d.

The pistons in the constructions of Figs. 1 to 7 are shown somewhat diagrammatic for the pur-

pose of illustration, but it must be understood that these pistons may be sector-shaped, as shown in the constructions of Figs. 7 to 10.

The application of the rotary piston machine, according to the present invention, is not limited to the uses described above. It is possible to use such machines in a number of other fields without departing from the principle of the rotary pistons according to the invention.

It must be understood that the pistons in the construction of Figs. 7 to 10 may be hollow if desired.

It must also be understood that blocking means may be provided for preventing the rotation of the pistons in undesired directions.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters Patent, is:

1. A rotary piston machine comprising a working chamber having an inlet and an outlet, a pair of rotary pistons coaxial with said chamber and operable therein, a pair of arms outside of said chamber and connected to said pistons, a rotary cross-head outside of said chamber and engaging said arms, a bearing for said cross-head outside of said chamber, the axis of said bearing

being eccentric in respect to the axis of said pistons, whereby upon rotating said cross-head differential movement is imparted to said pistons, and means for adjusting the position of said bearing radially with respect to the axis of said pistons to vary the extent of differential movement between said pistons.

2. A rotary piston machine having an annular working chamber having an inlet and an outlet, a pair of pistons in said chamber and rotatable about the axis of said chamber, a pair of concentric shafts connected to said pistons and extending to the exterior of said chamber, a pair of arms connected to said shafts outside of said chamber, a third shaft eccentrically disposed in respect to said chamber and having a slotted cross-head engaging said arms, and means for adjusting the position of said last mentioned shaft in a direction radial of said chamber.

3. A rotary piston machine having an annular working chamber having an inlet and an outlet, a pair of pistons in said chamber and rotatable about the axis of said chamber, a pair of concentric shafts connected to said pistons and extending to the exterior of said chamber, a pair of arms connected to said shafts outside of said chamber, a third shaft eccentrically disposed in respect to said chamber and having a slotted cross-head engaging said arms, and means for vertically adjusting said last mentioned shaft radially of said chamber to thereby vary the eccentricity of the latter and to vary the extent of differential movement of said pistons.

PAUL SOBEK.
